CLAIM

We claim the ornamental design for a computer, as shown and described.

DESCRIPTION

FIG. 1 is a front perspective view of the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines formed by dashes show unclaimed subject matter and form no part of the claimed design. The broken away symbols in the drawings indicate the appearance of the break lines and any portion of the article between the break lines forms no part of the claimed design.
